UNITED STATES PATENT OFFICE.

ANTHONY L. McHUGH, OF CINCINNATI, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

MOTOR-CONTROLLER.

No. 902,101.

Specification of Letters Patent.

Patented Oct. 27, 1908.

Application filed June 30, 1906. Serial No. 324,165.

To all whom it may concern:

Be it known that I, ANTHONY L. McHUGH, citizen of the United States, residing at Cincinnati, in the county of Hamilton and State 5 of Ohio, have invented certain new and useful Improvements in Motor-Controllers, of which the following is a full, clear, and exact specification.

My invention relates to multiple voltage 10 controllers.

In the patent to Dunn No. 797,271, granted Aug. 15, 1905, there is described a multiple-voltage controller in which a fixed resistance is temporarily cut into the armature circuit whenever the connections of the armature are changed from one set of mains to another. This resistance, now commonly known as a buffer resistance, serves to prevent excessive surges of current through the 20 armature when the impressed voltage thereon is either increased or decreased. In the Dunn patent this buffer resistance is inserted in circuit by raising one of the contact fingers from the controller drum, thereby opening a 25 short circuit around the resistance. This is found to be an unsatisfactory way, because of the double movement of the drum and the finger, and because there is only a point or line contact between the finger and its co- 30 operating contact segment on the drum. The present invention is intended to overcome this difficulty by having the buffer resistance inserted by a switch separate from the controller drum and its fingers, but operated by the drum in its rotation.

In one aspect my invention consists of the combination of a controller arranged to impress different voltages on a motor armature, with a resistance in the motor armature circuit, and a mechanically operated switch 40 separate from the controller drum and its co-operating contact fingers and arranged to normally short-circuit said resistance but to open said short-circuit whenever the voltage 45 impressed on the motor armature is varied.

In a more specific aspect my invention consists of a multiple-voltage controller, a motor controlled thereby, a resistance in the armature circuit of said motor, a switch 50 biased to closed position to short-circuit said resistance, said switch being separate from the controller drum but arranged to be opened thereby to include said resistance in the armature circuit whenever the armature

connections are changed from one set of mains to another, and a device for retarding the closing of said switch.

Other features of my invention will appear hereinafter.

Figure 1 is an elevation of part of a controller embodying my invention, with the casing partly broken away in order to show the operating mechanism. Fig. 2 is a section on line 2—2 of Fig. 1; and Fig. 3 is a diagrammatic view showing a development 65 of the controller.

In the drawings, 31 is the controller drum operable by the usual handle 32. For the sake of simplicity the connections of the controller drum here indicated are approximately the same as in the patent to Dunn aforesaid, but it is obvious that my invention is applicable to any other form of controller in which the voltage impressed on a motor armature is varied and especially applicable 70 to any form of multiple voltage controller. The controller drum has contact segments 33 arranged to coöperate with contact fingers 34 to 39 inclusive, to connect the armature of motor M to different sets of the mains a, b, c 75 and d. The drum also has a ring 40 and segments 41 arranged to coöperate with contact fingers 42 to 48 inclusive to vary the resistance r in the field circuit of motor M.

Mounted on the shaft of the controller 85 drum is a cam wheel 49, on the periphery of which rides a roller 50 carried by a lever 51. The cam wheel 49 is shown developed in Fig. 3, but in order to show more clearly the operation of the device, is there shown as if its 90 cam projections were on its upper surface instead of on its periphery. These cam projections are so located that they engage with and move roller 50 as the motor armature connections are being changed from one set 95 of mains to another. The lever 51 is connected to a switch 52 which tends to close and remain closed because of the spring 53. The lever 51 and switch 52 are also connected by a link 54 to a second lever 55. The other 100 end of this lever 55 is connected to the piston rod of a dash-pot or other time-limit device 56, pivoted at 56^a. The dash-pot 56 is constructed in any desired manner so as to allow movement freely in one direction but to retard movement in the other direction. The rate of the retardation is adjustable by a stop cock 57. The switch 52, when closed, short-

circuits a resistance R in the motor armature circuit, but when opened breaks the short-circuit to effectively include the resistance in said armature circuit. By the arrangement of levers here set forth a small movement of the roller 50 causes a large movement of the switch 52, and a still larger movement of the dash-pot. Moreover with the switch 52 and the dash-pot 56 on opposite sides of the controller, and both near the outside casing, it is easy to inspect and repair both of them. To inspect the dash-pot it is only necessary to remove pin 55^a and swing the dash-pot around on its pivot 56^a.

When the controller is moved to change the armature connections from one set of mains to another, the cam projections on cam wheel 49 move lever 51 to open the switch 52, and to include the resistance R in the motor armature circuit. The movement of the switch 52 is not retarded in this direction. As soon as the change of armature connections has been made, the spring 53 begins to expand to force the switch 52 toward closed position. This movement of the switch, however, is retarded by the dash-pot 56 until the switch is nearly closed, when a by-pass 58 around the piston of the dash-pot is reached, thus allowing a quick closing movement of the switch 52. In the controller shown the resistance R is included in circuit when the controller passes between positions 7 and 8, 14 and 15, 18 and 19, 21 and 22, and 23 and 24, and also when it passes to or from "off" position. Between the positions just mentioned the armature connections are changed from one set of mains to another. Between any other two adjacent positions, the controller merely varies the resistance r in the field circuit of the motor. This field resistance is arranged to be increased as the controller is moved forward between those adjacent positions where the armature connections are not varied, thus increasing the speed of the motor, but to be cut out whenever the armature connections are varied, thus insuring a strong field whenever a higher voltage is impressed on the armature.

It is obvious that the part of the controller which controls the field resistance may be varied as desired, and that the part which controls the armature connections may be adapted to any multiple-voltage system and arranged if desired to reverse the armature current. These modifications as well as many others which readily occur to one skilled in the art may be made without departing from the spirit of my invention, and are intended to be covered by the following claims.

What I claim is:—

1. A controller arranged to impress different voltages on a motor armature, a resistance in the motor armature circuit, and a

mechanically operated switch separate from the controller drum and its co-operating contact fingers and arranged to normally short-circuit said resistance, but to open said short-circuit whenever the voltage impressed on the motor armature is varied. 70

2. A multiple-voltage controller, a motor controlled thereby, a resistance for the armature circuit of said motor, a switch normally closed to short-circuit said resistance, 75 said switch being separate from the controller drum but arranged to be opened thereby to effectively include said resistance in the armature circuit whenever the armature connections are changed from one set 80 of mains to another.

3. A multiple-voltage controller, a motor controlled thereby, a resistance in the armature circuit of said motor, a switch normally closed to short-circuit said resistance, said 85 switch being separate from the controller drum but arranged to be opened thereby to break said short-circuit whenever the armature connections are changed from one set of mains to another, and a device for retarding 90 the closing movement of said switch.

4. A multiple-voltage controller, a motor controlled thereby, a resistance for the armature circuit of said motor, a switch normally closed to short-circuit said resistance, said 95 switch being separate from the controller drum but arranged to be opened thereby to effectively include said resistance in the armature circuit whenever the armature connections are changed from one set of mains 100 to another, and means tending to close said switch.

5. A multiple-voltage controller, a motor controlled thereby, a resistance in the armature circuit of said motor, a switch normally 105 closed to short-circuit said resistance, said switch being separate from the controller drum but arranged to be opened thereby to break said short-circuit whenever the armature connections are changed from one set of 110 mains to another, means tending to close said switch, and a time-limit device for retarding such closure.

6. A multiple-voltage controller, a motor controlled thereby, a resistance for the armature circuit of said motor, a switch normally closed to short-circuit said resistance, said 115 switch being separate from the controller drum but arranged to be opened thereby to include said resistance in the armature circuit whenever the armature connections are changed from one set of mains to another, and a dash-pot for retarding the closing movement of said switch while allowing a 120 free opening movement thereof.

7. A multiple-voltage controller, a motor controlled thereby, a resistance in the armature circuit of said motor, a switch normally closed to short-circuit said resistance, said 130 switch being separate from the controller

drum but arranged to be operated thereby to open said short-circuit whenever the armature connections are changed from one set of mains to another, and a dash-pot for 5 retarding the closing movement of said switch.

8. A multiple-voltage controller, a motor controlled thereby, a resistance in the armature circuit of said motor, a switch normally 10 closed to short-circuit said resistance, said switch being separate from the controller drum but arranged to be operated thereby to open said short circuit whenever the armature connections are changed from one 15 set of mains to another, and means for retarding part of the closing movement of said switch, but arranged to allow the remainder of said closing movement to be unretarded.

9. A multiple-voltage controller, a motor 20 controlled thereby, a resistance in the armature circuit of said motor, a switch normally closed to short circuit said resistance, said switch being separate from the controller drum but arranged to be operated thereby 25 to open said short circuit whenever the armature connections are changed from one set of mains to another, and a dash-pot for retarding part of the closing movement of said switch, but arranged to allow the remainder 30 of said closing movement and all of the opening movement of the switch to be unretarded.

10. A multiple-voltage controller, a motor controlled thereby, a resistance, a switch 35 normally closed to short-circuit said resistance, said switch being separate from the controller drum but arranged to be opened thereby to include said resistance in the armature circuit whenever the armature connections are changed from one set of mains 40 to another, means for closing said switch, and a dash-pot for retarding such closure.

11. A multiple-voltage controller, a motor controlled thereby, a resistance for the armature circuit of said motor, a switch normally 45 closed to short-circuit said resistance, said switch being separate from the controller drum but arranged to be opened thereby to include said resistance in the armature circuit whenever the armature connections are changed from one set of mains 50 to another, means tending to close said switch, and a dash-pot for retarding such closure while allowing a free opening movement of the switch.

12. In a motor control system, multiple-voltage mains, a motor, a drum controller for connecting the motor armature to different sets of the mains, a resistance in the armature circuit of the motor, a switch separate 60 from the controller and biased to closed position to short-circuit said resistance, and means whereby a movement of the controller between certain positions opens said switch.

65 13. In a motor control system, multiple-

voltage mains, a motor, a drum controller for connecting the motor armature to different sets of the mains, a resistance in the armature circuit of the motor, a switch separate from the controller and biased to closed 70 position to short-circuit said resistance, means whereby a movement of the controller between certain positions opens said switch, and a time-limit device for retarding the closure of said switch.

75 14. In a motor control system, multiple-voltage mains, a motor, a drum controller for connecting the motor armature to different sets of the mains, a resistance in the armature circuit of the motor, a switch separate from the controller and biased to closed position to short-circuit said resistance, means whereby a movement of the controller between certain positions opens said switch, and a dash-pot for retarding the closing of 80 said switch.

85 15. A motor control system comprising a motor, multiple-voltage supply mains, a controller arranged to connect the motor armature between different sets of the mains and to vary the resistance in the motor field circuit, a resistance in the motor armature circuit, and a switch separate from the controller drum but arranged to be operated thereby to include said resistance in circuit 90 whenever the armature connections are changed to a different set of mains.

95 16. A motor control system comprising a motor, multiple-voltage supply mains, a controller arranged to connect the motor armature between different sets of the mains and to vary the resistance in the motor field circuit, a resistance in the motor armature circuit, and a switch separate from the controller drum but arranged to be operated 100 thereby to include said resistance temporarily in circuit whenever the armature connections are changed to a different set of mains, said switch being free from movement by the controller when the latter 110 merely varies the field resistance.

115 17. In a controller, a rotatable drum, a switch separate from said drum and arranged to be opened by said drum when the latter is moved between certain positions, means which tends to close said switch, and a dash-pot for retarding said closing, said switch and said dash-pot being on opposite sides of the drum.

120 18. In a controller, a rotatable drum, a switch separate from said drum and arranged to be opened by said drum when the latter is moved between certain positions, means which tends to close said switch, a dash-pot for retarding said closing, and connecting levers whereby the piston of said dash-pot has 125 a greater movement than the switch.

130 19. In a controller, a rotatable drum, a switch separate from said drum and arranged to be opened by said drum when the latter is

moved between certain positions, means which tends to close said switch, a dash-pot for retarding said closing, and levers so arranged that a small movement of the drum causes a large movement of the switch.

20. In a controller, a rotatable drum, a switch separate from said drum and arranged to be opened by said drum when the latter is moved between certain positions, means which tends to close said switch, a dash-pot

for retarding said closing, and levers so arranged that a small movement of the drum causes a large movement of the switch and a still larger movement of the dash-pot piston.

In testimony whereof I affix my signature, 15
in the presence of two witnesses.
